BOX MAKING APPARATUS

Ernest C. Clement, 315 N. Euclid, Oak Park, Ill.

Filed Jan. 3, 1956, Ser. No. 556,950

6 Claims. (Cl. 74—26)

This invention relates to apparatus for making boxes of the paperboard type. In particular the invention deals with apparatus for imparting reciprocative movement to a box forming plunger.

The apparatus of this invention advantageously may be used, for example, with the box making die shown in my co-pending application entitled "Box Making Die," Serial No. 424,149, filed April 19, 1954. The die there shown is characterized by extreme flexibility as to the sizes of boxes which may be formed thereby. The present apparatus contemplates a series of different sized plungers which cooperates with the adjustable die shown in the prior application in order to provide a single machine capable of forming boxes in an extremely wide range of sizes and at high speed. Such a machine is here called a multi-purpose machine.

As more fully set forth in my prior application, boxes made with apparatus of this type are constructed of paperboard which is formed to desired shape in the apparatus and then glued at suitable points to retain the shape.

Generally speaking, present machines used in the forming and gluing of paperboard boxes employ two common elements, a plunger which conforms to the inside dimensions of the box to be formed, and a die which forms a previously flat box blank around the plunger. Ordinarily the die is stationary, and a flat box blank is brought to rest either above or below the die. The plunger then enters the die from above or below, as the case may be, and the box blank takes the form of the plunger from the action of the die which conforms to the outside dimensions of the box to be formed.

A machine designed to make a box of a single size only, here called a single purpose machine, is so constructed that the length of stroke of the plunger is appropriate to the vertical dimension of the box. With such a machine the maximum production speed which may be obtained usually is determined by the length of the plunger stroke required to form the box and the inertia factors of the plunger itself in acceleration and deceleration.

Since portions of the box are glued together, pressure must be exerted on these portions after the plunger has entered the die and imparted proper shape to the box. To permit the application of this pressure, it is necessary to provide a dwell at the extended end of the plunger stroke. Therefore the plunger may not be driven by a constant speed crank which results in a simple sine curve type of motion having no dwell to accommodate the pressure requirement.

At the withdrawn end of the plunger stroke the plunger must be separated from the die a sufficient length of time to permit the positioning of a box blank in effective relation with the die. If a sine curve type of motion were applied to the plunger in this withdrawn portion of the stroke, the length of the stroke would be excessive in order to permit the positioning of a blank on the die, or the length of time allotted to the blank positioning step would be excessively brief. Therefore a sine curve type of motion likewise is not suitable for the plunger at the withdrawn end of its stroke.

In general, prior single purpose machines have used a

2

cam to impart proper motion to the plunger, the cam being designed to provide dwells at the extended and withdrawn ends of the stroke to permit glue pressure application at the extended end of the stroke and to permit positioning of the blank at the withdrawn end of the stroke. With a carefully designed cam it is possible to provide a single purpose machine which operates at the maximum possible speed within the limitations imposed by required stroke length and the inertia factors of the plunger and associated drive elements.

The present apparatus, however, does not contemplate a single purpose machine. Rather it contemplates a machine capable of making boxes in a wide range of sizes, a multi-purpose machine. A multi-purpose machine constructed in accordance with the prior art presents a serious design dilemma. It is, of course, advantageous in any automatic box making machine that the productivity be a maximum at all times, since the primary purpose of automatic equipment is to increase production.

Some multi-purpose machines appear in the prior art, and these machines employ a cam, as described above, to impart the desired motion, including the aforesaid dwells, to the plunger. In such a machine the length of plunger stroke necessarily is determined by the vertical dimension of the maximum sized box that can be made on the machine. The speed or productivity of the machine is thereby established as a function of the inertia factors of the plunger in acceleration and deceleration for the set stroke length. When the machine is used for a box of smaller or minimum vertical dimension, the same factors remain in control, and the maximum speed attained on the smaller box still is a function of the limitations which apply to the largest box. The result is either a severe limitation on speed, or a severe limitation on the range of box sizes that can be handled in the machine, or both.

To solve the design dilemma described above, the present invention utilizes an adjustable-length crank which provides variability in the length of the plunger stroke. This permits the stroke length to be varied advantageously according to the requirements of a particular box size. An adjustable crank alone, however, does not solve the problem for the reason, mentioned above, that a constant speed crank provides a sine curve type of motion wherein the required dwells are lacking.

In addition to the adjustable length crank the invention employs a cam, here called a rate cam, which, as will be seen, is effective to change the rate at which the crank moves during various parts of its rotary cycle. The crank rate is adjusted to zero at the extended and withdrawn ends of the plunger stroke to provide the required dwells, and the length of the crank then easily can be adjusted to provide optimum stroke lengths for various box sizes.

The motion provided by the present rate cam requires differentiation before it provides the desired result in controlling the motion of the crank. This differentiation is obtained by means of a differential system in which a constant speed input is modified by the varying speed movement provided by the rate cam, the output motion of the differential system being proper for the crank which drives the plunger.

Other objects, advantages and features of the invention will be apparent as the description proceeds, reference being had to the accompanying drawing wherein one form of the invention is shown. It is to be understood that the description and drawing are illustrative only and that the scope of the invention is to be measured by the appended claims.

In the drawing:

Fig. 1 is a somewhat diagrammatic elevational view of box making apparatus embodying the invention, and

Fig. 2 is a plan view of a portion of the apparatus showing the differential system here employed.

Referring now to the drawing, apparatus embodying the invention includes a box forming plunger 5. The precise shape of plunger 5 is not a feature of the invention, but ordinarily such a plunger in plan view is square or rectangular. Since the external dimensions of plunger 5 conform to the internal dimensions of a box to be formed thereby, a multi-purpose machine embodying this apparatus utilizes a series of different sized plungers 5, there being one plunger for each box size.

As previously mentioned, a plunger 5 cooperates with a box making die such, for example, as the adjustable die shown in my aforesaid application Serial No. 424,149.

Plunger 5 is carried by a slider 6 arranged for reciprocative movement in one or more bearings 7. A plunger 5 is detachably mounted on slider 6 as indicated at 8 so the respective plungers 5 readily may be interchanged.

Slider 6 and associated plunger 5 are driven by means of a rotating crank 10 carried on a crankshaft 11 which is rotated at varying speed, as will be seen. The varying speed of crankshaft 11 is such that two substantial-duration dwells occur in each revolution of the shaft, thus to provide the required plunger dwells at the extended and withdrawn ends of the plunger stroke.

A suitable driving connection such as a link 12 extends between crank 10 and slider 6, link 12 being pivoted at its ends to the crank and slider. The effective length of crank 10 is adjustable to vary the stroke length of plunger 5, and as here shown, crank 10 has an elongated slot 13 near its free end. Suitable means 14 on link 12 or the crank pin permit the adjustment of the pivoted end of link 12 along crank 10 in a lengthwise manner. By this adjustment the stroke length of plunger 5 may be varied and set to be a minimum for each different sized box. As previously mentioned when stroke length is a minimum, machine speed and productivity can be a maximum.

Apparatus for driving crankshaft 11 at the desired varying speed now will be described, it being understood that crankshaft 11 makes one complete revolution or cycle during the formation of a single box. Thus, crankshaft 11 may be termed a cycle shaft which rotates at varying speed with two dwells per revolution.

Apparatus embodying the invention includes two other shafts which also may be termed cycle shafts in that they rotate through one revolution for each cycle of box formation. These two shafts, unlike crankshaft 11, rotate at constant speed during a given run of machine operation. This speed, however, may be varied as between successive runs depending on the size of the box being formed. Such speed will be relatively slow for the larger boxes and relatively fast for the smaller boxes, these box sizes, of course, being a measure of the required stroke length and inertia of the plunger.

One of these two shafts is a constant speed first shaft 20 and the other is a constant speed second shaft 21. As previously mentioned, shafts 20 and 21 make one revolution or cycle at constant speed for each box.

Shafts 20 and 21 are driven in any suitable manner as by sprockets 22 and 23 respectively keyed thereon, the sprockets being engaged by an endless chain 24 driven by a driving sprocket 25 carried on a driving shaft 26. Since sprockets 22 and 23 are identical in size, shafts 20 and 21 are driven at the same speed by chain 24.

A rate cam 30, keyed on constant speed first shaft 20, is engaged by a cam follower 31 which is carried by an arm 32 pivoted on a fixed shaft 33. Thus, cam follower 31 oscillates in accordance with the shape of rate cam 30. A link 35, pivoted at one end to cam follower 31, has its other end pivoted at 36 to an eccentric point on a first sprocket 37 which is carried on a shaft 38. First sprocket 37 thus is driven in an oscillating manner by link 35 which in turn is connected to oscillating cam follower 31.

Referring again to constant speed second shaft 21, a second sprocket 40 is journaled for rotation on shaft 21. Suitable means such as endless chain 41 interconnects first sprocket 37 and second sprocket 40 so that the latter oscillates in synchronism with the former. Second sprocket 40 could, of course, be driven directly from cam follower 31 if desired. It will be remembered that second shaft 21 on which sprocket 40 is journaled rotates at constant speed through one revolution for each box making cycle.

A three-gear differential system, generally designated 45 in Fig. 2, is disposed in operative relation with second sprocket 40 and constant speed second shaft 21.

In the form of the invention shown, differential system 45 includes an idler miter gear 46 journaled for rotation on a stub shaft 47 extending from hub 48 (Fig. 2) of second sprocket 40. As shown in Fig. 1, second sprocket 40 is cut away at 49 to accommodate stub shaft 47 and idler miter gear 46. The axis of idler miter gear 46 thus extends normal to constant speed second shaft 21, and this axis oscillates back and forth with second sprocket 40 through a partial revolution.

An input miter gear 50 (Fig. 2), keyed to second shaft 21, rotates at constant speed with shaft 21. Input miter gear 50 meshes with idler miter gear 46, as shown in Fig. 2.

An output miter gear 52, best shown in Fig. 2, is journaled on second shaft 21 in engagement with idler miter gear 46. The instantaneous speed of rotation of output miter gear 52 is a function of the instantaneous speeds of idler miter gear 46 and input miter gear 50, and this output speed varies because of the varying speed provided by the oscillations of idler miter gear 46.

With proper design of rate cam 30, the varying-speed rotary motion developed by output miter gear 52 is suitable for driving plunger 5 by means of a simple crank. Although a crank effectively could be mounted on output miter gear 52, the present embodiment of the invention contemplates a direct driving connection extending between output idler gear 52 and the aforesaid crankshaft 11.

As here shown, a sprocket 55, associated with output miter gear 52, drives an endless chain 56 which engages and drives a sprocket 57 keyed to crankshaft 11. Thus crankshaft 11 is driven with the same varying speed as that of output miter gear 52.

As previously described, the varying speed of crankshaft 11 is communicated to plunger 5 by means of adjustable-length crank 10 and pivoted link 12, the latter engaging slider 6 which reciprocates on a straight line and carries plunger 5.

The instantaneous speeds of the respective miter gears of the illustrated differential system are related as follows:

$$Z = \frac{X+Y}{2}$$

where:

X is the instantaneous rate of rotation of output miter gear 52,

Y is the uniform rate of rotation of input miter gear 50, and

Z the instantaneous rate at which idler miter gear 46 oscillates around second shaft 21.

A more general form of Equation 1 is:

$$Z = \frac{X-EY}{1-E} \quad (2)$$

where:

E is the ratio of the number of teeth on input miter gear 50 to the number of teeth on output miter gear 52, the other variables being as described above. The ratio E has negative sense when there is an odd number of miter gears, as here, and positive sense when there

is an even number. Since gears 50 and 52 have the same number of teeth in the illustrated differential system the ratio E is (-1).

The directions of rotation of constant speed shafts 20 and 21 are immaterial so long as rate cam 30 is shaped properly. As indicated by the above equations, if the two shafts 20 and 21 rotate in the same direction, then crank 10 turns in one direction, but if the two shafts rotate in opposite directions, then crank 10 turns in the other direction.

When rate cam 30 imparts proper oscillatory motion to second sprocket 40, idler miter gear 46 oscillates in such manner that output miter gear 52 has the proper two dwell periods for desired plunger operation.

By way of example, during each 360° cycle of constant speeds shafts 20 and 21, 90° each may be allocated to the dwells at the extended and withdrawn ends of the stroke, and 90° each may be allocated to the outward and inward strokes.

The dwell pattern having been established by rate cam 30 to the most advantageous form, variable-length crank 10 may be adjusted to provide a length of stroke most appropriate to the particular box being formed. In this manner the maximum speed of the machine on a particular box may be that which is most advantageous for that box, and the average speed of the machine for all boxes is raised considerably from that which has been possible on prior multi-purpose machines.

One further feature in connection with adjusting the plunger stroke for optimum length needs to be mentioned. The die element with which the plunger cooperates has a fixed position in the machine, and the paperboard box blank is fed to a fixed position in relation to the die. Therefore it is desirable that the plunger have a terminal position at the withdrawn end of the stroke that is substantially the same for all box sizes and stroke lengths. In other words, the stroke length variation provided by the apparatus is reflected in the terminal position of the plunger at the extended end of the stroke.

The substantially uniform terminal position at the withdrawn end of the plunger stroke is provided by suitable adjustment of the driving connection between crank 10 and slider 6. As here shown, an elongated slot 60 is provided in slider 6 and cooperating adjustable means 61 establishes proper relationship between link 12 and a desired point on slider 6 along slot 60. Thus an adjustment may be made on slider 6 to compensate for the stroke-length adjustment made on crank 10 in order to preserve the proper terminal position of the plunger at the withdrawn end of the stroke.

In practice, a multi-purpose machine embodying the present invention is capable of a range of box sizes which is roughly double that of any comparable prior multi-purpose machine, and the productivity rate on any particular size is approximately equal to that attained by any comparable single purpose machine, such productivity rate being considerably greater than that possible on prior multi-purpose machines.

From the above description it is thought that the construction and advantages of my invention will be readily apparent to those skilled in the art. Various changes in detail may be made without departing from the spirit or losing the advantages of the invention.

Having thus described my invention, what I claim as new and desire to secure by Letters Patent is:

1. Apparatus for imparting reciprocative movement to a box making plunger wherein a substantial dwell period is provided at each end of the plunger stroke, said apparatus comprising a constant speed first shaft, a rate cam keyed on said first shaft, a cam follower engaging said cam, an oscillating first sprocket driven by said cam follower whereby said first sprocket has one cycle of oscillation for each rotary cycle of said first shaft, a constant speed second shaft, a drive means imparting a constant speed to said first and second shafts, a second sprocket

journalled on said second shaft, means interconnecting said first and second sprockets for synchronous oscillation, an idler miter gear carried by said second sprocket on an axis normal to said second shaft, an input miter gear keyed to said second shaft and engaging said idler miter gear, an output miter gear journalled on said second shaft and engaging said idler miter gear, a crank, said output miter gear drivingly connected to said crank, and a driving connection between said crank and said plunger.

5 2. The combination of claim 1 wherein said crank is adjustable in length whereby the total stroke of said plunger may be varied to be a minimum for each of various different effective strokes.

3. Apparatus for imparting reciprocative movement to

15 a box making plunger wherein a substantial dwell period is provided at each end of the plunger stroke, said apparatus comprising a constant speed input differential gear which rotates one revolution per reciprocative cycle of said plunger, a drive means imparting a constant speed to

20 said input differential gear, an idler differential gear engaging said input differential gear, a shaft on which said idler differential gear is mounted for rotation, said shaft having a right angle relation with the axis of said input differential gear and mounted for radial oscillation on said

25 axis as a center, means imparting continuous radial oscillation to said shaft at a rate whereby there is one cycle of oscillation per revolution of said drive means, a varying speed output differential gear engaging said idler differential gear, a crank, said output differential

30 gear drivingly connected to said crank, and a driving connection between said crank and said plunger.

4. The combination of claim 3 wherein said crank is adjustable in length whereby the total stroke of said plunger may be varied to be a minimum for each of various different effective strokes.

5. Apparatus for imparting reciprocative movement to a box making plunger wherein a substantial dwell period is provided at each end of the plunger stroke, said apparatus comprising a constant speed first shaft, a rate cam keyed on said first shaft, a cam follower engaging said cam and driven thereby in an oscillatory manner whereby said cam follower has one cycle of oscillation for each rotary cycle of said first shaft, a constant speed second shaft, a drive means imparting a constant speed to said first and second shafts, a sprocket journalled on

45 said second shaft, means interconnecting said cam follower and said sprocket for synchronous oscillation, an idler miter gear carried by said sprocket on an axis normal to said second shaft, an input miter gear keyed to said second shaft and engaging said idler miter gear, an output miter

50 gear journalled on said second shaft and engaging said idler miter gear, a crank, said output miter gear drivingly connected to said crank, and means connecting said crank to said plunger.

55 6. The combination of claim 5 wherein said crank is adjustable in length whereby the total stroke of said plunger may be varied to be a minimum for each of various different effective strokes and wherein said means connecting said crank to said plunger is adjustable to provide a predetermined terminal plunger position at the withdrawn end of the stroke regardless of stroke length.
